W. H. Howard.

Loom.

Patented Feb. 12, 1830.

William H. Howard.

Inventor

The schedule referred to in the Boston Patent and making part of the same containing a description in the words of the late William H. Howard himself of his improvement in the Power Loom called "Improved vibrating cam Loom."

To all persons to whom these presents shall come. William H. Howard of Worcester in the County of Worcester, State of Massachusetts machine-
sit and greeting. Be it known that I the said Howard have in-
vented made & applied to use a new & useful improvement in the power
loom called the "Improved vibrating cam Loom" as specified in the words
following. Broad looms such as have been and are now in general use
are constructed with a frame of sufficient length to receive the desired
width of cloth & of width enough to admit the lathe to vibrate and the
harness to pass the warp for the passage of the shuttle. It has a shaft called
a main shaft extending the length of the loom & is placed nearly in the
center of the frame. On each end of said main shaft are counter shafts or sweeps.
The lathe is supported on pivots at the bottom and near one corner of the
frame. The perpendicular part of the lathe at the end on which it rests &
vibrates are called "Lathe Standards." The lathe is put in motion by
means of an arm extending from the counter on the main shaft to the back
end of the lathe. The shuttle & harness are put in motion by means of cams on
a shaft lying under the main shaft & connected with the said main shaft
some way from the end. The cams are in the centre of the loom & supported by
a support. The looms as above described are called "warp looms" &
are found to answer a valuable purpose for weaving narrow cloth, but for
weaving broad cloth they are not considered suitable on account of the
motion of the lathe experienced by the warp giving sufficient time
for the shuttle to pass before the lathe comes to rest on the sweep. To obviate
this difficulty various methods have been introduced. The most effect-
ual one I will endeavor to describe in the words following viz:

(5826)

view about two feet in length is placed transversely underneath of
the main staff. the bottom of which is supported on a pivot made fast to
the end of the lower frame directly under the main staff. On the top of this
pivot is a weight of a circular form & the pin on the main staff this weight
and of course produces a vibrating motion to the upright piece above
described which is called the "vibrating case." The motion is given to the
table by arms extending from the "vibrating case" to the table in the same
manner as on the crank form. The two forms already described resem-
ble each other in every other respect than that of giving a derived motion to
the table by means of the vibrating case. I do not however claim any in-
vention in the forms already specified as my improvement, but I do
claim the particular method of applying the vibrating case immediately
simply & effectively than ever before done & also that of the upright, hori-
zontal and my improvement in reference to the base to the screwing de-
tails in the Patent Office. My improvement consists in making
the circular pieces called "vibrating cases" as above on the table stand
and instead of having a separate piece for that purpose alone, I ²nd that of
applying the upright so as to admit of the case standing said upright
& that part called the "sway staff" being hung on a pivot on the upright.
Submitting that the above is a true specification of my improvement as
above described. I have hereunto set my hand & seal this twenty fifth day of
November in the year of our Lord one thousand eight hundred and four
years.
